United States Patent Office

Des. 204,686
Patented May 10, 1966

204,686

FACIAL TISSUE DISPENSER

Charles O. Bliss, P.O. Box 47607, Los Angeles, Calif.

Filed Aug. 16, 1965, Ser. No. 86,583

Term of patent 14 years

(Cl. D52—2)

FIG. 1 is a top plan view of the facial tissue dispenser showing my new design;

FIG. 2 is a front view in elevation thereof;

FIG. 3 is a bottom plan view thereof;

FIG. 4 is a rear view in elevation thereof; and

FIG. 5 is an end view in elevation thereof.

I claim:

The ornamental design for a facial tissue dispenser, substantially as shown.
